FLYING BOAT

Franz Kleinhenz, Berlin-Treptow, Germany

Application May 27, 1931, Serial No. 540,304,
and in Germany June 2, 1930

3 Claims. (Cl. 244—2)

The constructions of flying boat that are customary today have various disadvantages, which show themselves particularly in the defective seaworthiness on the open. Up to the present five 5 distinct types of flying boat have been tested, namely:

1. A type with a comparatively narrow central boat and two supporting floats secured to the wings;
- 10 2. A type with lateral stump bodies on a central boat;
3. A type with a central boat and two supporting floats located in the neighbourhood of the boat.
- 15 4. A type constructed as an enlarged float aeroplane in the form of a double boat; and
5. A type with a central boat of sufficient breadth and transverse stability.
- 20 Only the constructions named under (2) and (5) can be regarded as intrinsically stable flying boats.

The constructions named above all have various disadvantages. Even when lateral stumps 25 or special supporting bodies are provided, the possibility of the water washing over them still exists in which case the flying boat suffers considerable loss of transverse stability, or may even lose it entirely. The latter is the case, with 30 single floats which are arranged beside a central boat, when one of the lateral floats entirely loses its buoyancy, by leakage for example. Double flying boats also have serious disadvantages, which exhibit themselves particularly when travelling across or along the waves.

A central aeroplane body will also in general be best able to fulfill the conditions of seaworthiness on a high sea.

The object of the present invention is to provide 40 an intrinsically stable flying boat, which avoids the disadvantages of special stability bodies, and the disadvantages of the float aeroplane and double boat.

In order to attain this aim the boat body is 45 built on special lines. Since in the case of a boat the boat body must also be the hull, these two bodies must have a coherent form and must be connected with one another by suitable transition surfaces. The hull is to be arranged, according 50 to its purpose, as nearly as possible in the central axis, while the actual boat, according to its purpose, that is to say, in order to attain the necessary transverse stability, should be arranged as far as possible away from the 55 central longitudinal axis of the boat.

The lateral floats must be located as far as possible from the central longitudinal axis of the boat, but not more so than is required by its union with the actual flying-boat hull. The connecting surfaces from the laterally arranged 60 floats to the actual central portions of the boat or hull are to be shaped as far as possible according to the requirements of aerodynamics. The problem is also to be so defined that these float surfaces to be arranged laterally are so 65 selected in their contours that a flooding of these bodies or an over-burdening by water when the boat heels over is as far as possible avoided. The connecting surfaces between the actual float 70 surfaces and the central boat body therefore begins in a convex or swelling line, and is continued to the central body in as stiff a form as possible. A float surface located in the vertical axis of the boat would give little or no assistance 75 in obtaining metacentric height, so this surface is entirely excluded from the boat body.

The new form based on these considerations 80 consists according to the invention of a central hull or boat body forming a whole, organically and aerodynamically, with members projecting towards the sides and downwards, the under surfaces of which form the float surfaces, in such a way that between the projecting members a tunnel shaped cavity is left, bounded by the internal 85 surfaces of the convex members and the under surface of the hull or boat body. The superstructure of the flying-boat body therefore takes its origin from the central hull and divides the float surfaces into two float surfaces separated from one another, for the purpose of connecting the actual float bodies mounted upon the float 90 surfaces in aerodynamic forms with the hull body, so that in the central longitudinal axis of the flying boat, from the vertex of the boat right to the stern or end of the hull, there remains free a tunnel-like space. The distance of the two 95 float bodies from one another is preferably kept somewhat below the usual distance of a two-float flying boat. The space remaining between the lateral float-body surfaces is constructed as high as possible so as not to hinder the discharge of the water. For the purpose of preventing the water from rising on the inner side walls in the tunnel at the start or landing of the flying boat, and to prevent accumulations of water occurring when the water flows in and out, the tunnel-shaped space is constructed in its outlines in the form of a slightly curved nozzle. In order to let the water in the tunnel flow away as smoothly as possible the float surfaces are suitably keeled, 100 105 110

this being done in such a way that the outer bilges are located higher than the inner ones. There are therefore actually two keels, which, if it were desired to assemble them in one line, 5 represent the middle keel of a bottom keeled outwards towards both sides. The form of boat described above is applicable to flying boats of any size, from single-motor flying boats right to multi-motor flying boats, as well as to single-decker 10 (or monoplane) flying boats, one-and-a-half-decker (or "sesqui-plane") flying boats, and double-decker or bi-plane flying boats. The central portion of the boat, which in general is preferably arranged as high as possible, may advantageously constitute the accommodation for 15 the driver and for the passengers. The transition spaces to the actual float bodies are preferably to be provided as larger rooms for the accommodation of passengers, while the lower 20 cavities of the lateral floats serve for carrying freight and working loads. For the shape of the boat it is characteristic that the two said lateral floats are assembled both in the bow and in the stern in an aerodynamically closed line, this being 25 the case both in plan and in elevation. On the whole, therefore, the main contour of the boat, according to both sections, forms as far as possible a streamline body. The lateral keels of the 30 two floats extend in a curved line or surface towards the apex of the bow, and the surfaces extending obliquely from the stern apex of the two side bodies similarly extend towards the end of the hull. The flying boat carries as usual at its tail end the elevation and steering mechanism. 35 The flying mechanism may be constructed as desired and mounted upon the flying-boat body in a known manner.

The invention is illustrated by way of example in the accompanying drawing, in which 40 Figure 1 shows a one-and-a-half-decker flying boat in side elevation. Figure 2 shows a plan of the same, and Figure 3 an end elevation. The hull-like central body *a* is located high above the actual floats *b*. Against this the two floats *b* bear snugly in convex surfaces. The transition surfaces between the hull body and lateral floats are denoted by *c*. These transition surfaces are constructed either as doubly curved or as parabolic surfaces. Both surface forms are completely convex before the transition point to the actual float surfaces, in order that there may be no loss displacement in the event of the boat having a list. The two keel lines of the lateral floats are denoted in Figure 1 by *d*. In the plan 45 of the flying boat in Figure 2, the keel lines *d* are shown extending to the stern end, opening out somewhat in order to obtain the aforementioned nozzle effect. The broadening of the keel lines opening out in the neighborhood of the bow need 50 only be trifling. The keel lines *d*, as Figure 2 shows, are carried at the bow in a curved line to the vertex of the bow, while in the stern they likewise terminate at the end of the hull in a curved line. 55 The tunnel-shape of the cross section of the boat will be recognized from Figure 3. The two keel lines are there denoted by *d*, while the crown of the tunnel surface is denoted by *e*.

70

75

The surfaces connecting the two keel lines *d* with the crown *e* of the tunnel are preferably parabolic. The convex lines that are connected with the actual float surface are denoted by *f* in Figure 3. They extend at the same time over the doubly curved intermediate surface of the side floats to the central hull body. The longitudinal section of the central hull body, in which the lower boundary surface at the same time represents the tunnel surface, as Figure 1 shows, is of an elongated spindle shape. The side floats, in their contour as seen in plan, as Figure 2 shows, extend in the bow towards the vertex of the bow and in the stern towards the rear end of the hull in such a way that a stream-line body is produced. The transition surfaces from the lateral floats to the vertex of the bow are denoted by *i*, while the transition bodies from the float stern to the end of the hull are denoted by *j*. At the vertex of the bow, therefore, the central hull body *a* and the two actual side floats *b* meet at a point, denoted by *k*. 80 85 90 95

In order to afford the pilot the freest possible view forwards and towards the sides, the cockpit is arranged opposite the vertex of the bow and raised somewhat above it. The cockpit is constructed projecting out of the actual contour of the boat, in order that the pilot may without difficulty be able to see over the boat in a forward direction, and if possible also in a rearward direction. 100 105 110

The motors are arranged as high up as possible. Similarly also the vertical and lateral steering mechanism is also to be arranged as far as possible above the surface of the water, and on this account is supported upon the upper surface of the rear end of the hull. 115 120 125

I claim:

1. A flying boat comprising in combination a main body portion and lateral lower float portions united with said main portion by outwardly and downwardly sloping sides so as to form a common streamlined body of a tunnel shaped cross section, the bottoms of said float portions being shaped in cross section so as to each ascend against the outer side from a keel forming the lower edge and the stern of said tunnel. 130

2. A flying boat as claimed in claim 1, wherein the keels are straight, seen from above, in their portions merging into the water. 135

3. A flying boat comprising in combination a main body portion, laterally extending lower float portions united with said main portion by outwardly and downwardly sloping sides so as to form a common streamlined body of tunnel shape, a supporting wing fastened to said body, and propellers with driving means arranged on said wing, the body being free for the reception of loads, the body being divided by floors into several compartments, an upper compartment in the narrow main body portion being constructed as a sitting room, a lower compartment extending through the largest available space immediately above the tunnel and being constructed as a bed room, and the float portions being free for dead loads. 140 145 150
